UNITED STATES PATENT OFFICE.

WILLIAM HERRICK, OF CHICAGO, ILLINOIS, ASSIGNOR TO THE MORGAN & WRIGHT, OF SAME PLACE.

HAIR-SHEDDER.

SPECIFICATION forming part of Letters Patent No. 663,897, dated December 18, 1900.

Application filed June 27, 1900. Serial No. 21,788. (No model.)

To all whom it may concern:

Be it known that I, WILLIAM HERRICK, of Chicago, county of Cook, State of Illinois, have invented a certain new and useful Improvement 5 in Hair-Shedders, of which the following is a specification, reference being had to the accompanying drawings, forming part thereof.

My invention contemplates an implement 10 for shedding or removing the old coat of hair from horses and other animals, but more particularly horses, and is designed to afford a method of quickly removing all loose hair from a horse, especially in the spring and fall, 15 when the animal commences to shed its coat.

In the accompanying drawings, Figure 1 is a perspective showing the back of a hair-shedder embodying the principles of my invention. Fig. 2 is a perspective showing the 20 face of the shedder. Fig. 3 is a plan showing the guard unbuckled and the two strap portions extended at each side. Fig. 4 is a section on line xx in Fig. 3.

A hair-shedder constructed in accordance 25 with my invention is preferably rectangular in form and composed mainly of rubber or rubber composition. The face of the hair-shedder is formed with a series of longitudinally-arranged flexible rubber webs. These 30 flexible rubber webs are parallel and connected at their ends by like transverse webs B, the edges of the longitudinal and transverse ribs or webs being in substantially the same horizontal plane. The back E of the hair-shedder is common to all of said webs, and may be reinforced with fabric C, the fabric being cut in the form shown in Fig. 3 and provided with two laterally-extending strap portions, which can be adjustably connected, 35 for example, by being buckled together to form the guard D. The hair-shedder thus provided with parallel webs and intervening cavities can be molded in any suitable man-

ner. It will be understood that the fabric can be vulcanized to the rubber. The hair-shedder 45 thus molded with longitudinal and end transverse ribs and a back is flexible and elastic throughout and will readily yield to the form of the animal upon which it is used, it being observed that the rubber back will bend in all 50 directions and that the webs will yield in accordance with any bending action of the back.

In use the hand is placed under the guard and the face of the implement applied to the animal's coat. A sidewise movement of the 55 hair-shedder operates to pull out the loose hair, the webs A being flexed laterally as a result of such sidewise movement and the hair thus pulled out by the friction of the rubber collecting in the cavities between the 60 webs. In this way all loose hair can be quickly removed as soon as the horse begins shedding its coat. Ordinarily it requires several weeks for a horse to completely shed its coat, and during such time the hair is constantly coming 65 out, making driving unpleasant. With my novel hair-shedder, however, the old coat can be entirely removed as soon as the shedding begins, thereby putting the horse in shape for immediate service. 70

What I claim as my invention is—

A flexible and elastic hair-shedder, comprising a series of longitudinal parallel webs; transverse webs at the ends of the longitudinal webs, with the edges of said longitudinal 75 and transverse webs all substantially in the same horizontal plane; and a back common to all of said webs, the whole being molded of rubber or rubber composition; and a sheet of fabric covering and united to the outer side 80 of the back and provided with a suitable hand-guard, substantially as described.

WILLIAM HERRICK.
